UNITED STATES PATENT OFFICE.

FREDERICK VAN DYKE CRUSER, OF BARBERTON, OHIO, ASSIGNOR TO THE DIAMOND MATCH COMPANY, OF CHICAGO, ILLINOIS, A CORPORATION OF ILLINOIS.

MATCH-MACHINE.

1,044,145.

Specification of Letters Patent. Patented Nov. 12, 1912.

Application filed April 27, 1912. Serial No. 693,622.

To all whom it may concern:

Be it known that I, FREDERICK VAN DYKE CRUSER, a citizen of the United States, and resident of Barberton, in the county of Summit and State of Ohio, have invented certain new and useful Improvements in Match-Machines, of which the following is a specification.

In an application for Letters Patent of the United States, Serial No. 676,895, filed February 10, 1912, by William A. Fairburn, *et al.*, is described a process of drying splints in which have been impregnated with a solution of chemicals to render the splints non-glowing after the splints, as finished matches, have been ignited and the flame extinguished; said process consisting, essentially, in submerging or dipping the wet splints in a bath of suitable material, such, for example, as paraffin, which is kept at a temperature sufficiently high to drive the solvent from the splints in the form of vapor. In carrying out the process in a match machine employing an endless carrier chain into which the splints are inserted row by row and thereby transported through the match making path, it is important that the vapor evolved from the solvent in the splints, be rapidly removed in order to obviate any liability of the condensation of the vapor on the metal plates of the carrier chain.

Accordingly, the present invention has for its primary object to provide, in a match machine of the character referred to, simple and efficient means whereby the removal of the vapor to a point of discharge remote from the chain is accomplished; and with this and other objects in view the invention consists in various novel features of construction and operation which will be hereinafter described and claimed.

In the drawings—Figure 1 is a side elevation, partly in section, of the paraffining mechanism of a match machine embodying the preferred form of my invention, portions of the impregnating tank and carrier chain being illustrated. Fig. 2 is a sectional end elevation of the said mechanism and adjuncts, one row of splints being indicated on the carrier chain as passing through the molten paraffin.

A designates a portion of an endless carrier chain of any known or approved type into which the splints are inserted in con-

secutive rows, and are thus transported through the match making path.

B designates a tank suitably located beneath the carrier, adapted to contain a solution of a chemical or chemicals into which the rows of depending splints on the chain are progressively dipped to a depth and for a period sufficient to accomplish the efficient impregnation of the splints; the chemicals being of such a nature as to render the splints nonglowing when the splints, as finished matches, have been ignited and the flame extinguished. This tank is supported in any suitable manner, and the trackway *a* for the chain is appropriately constructed (as at *a'*) to effect the depression of the traveling plates or sections of the chain toward the tank so as to dip the depending splints for a sufficient period in the impregnating solution, then guide the plates or sections above the top of the tank to maintain the splints for a sufficient period in the solution, and then raise such plates or sections to withdraw the splints from the solution and permit the progress of the chain with the impregnated splints.

C designates a tank containing the vaporizing substance into and through which the splints are carried after they leave the impregnating tank. In the present instance the tank is designed to contain liquid paraffin which is maintained at a temperature sufficiently high to expel the solvent from the splints in such manner that the splints shall be effectively dried without deteriorating or lessening the efficacy of the nonglowing chemical or chemicals with which they are impregnated, which splints shall also at the same time absorb sufficient paraffin to facilitate their burning.

The tank herein illustrated comprises a vessel of suitable length, width and depth for its intended purpose, arranged beneath the route of the chain. The vessel is preferably double-walled or jacketed for the passage of steam or other heating agent from a suitable source of supply, whereby the paraffin contents of the vessel may be readily raised to a temperature above 250° F. On the sides of this vessel are arranged jacketed reservoirs C' for liquid paraffin, which may be supplied to the tank in any suitable manner, such, for example, as by the automatic ladles or pumps usually employed in connection with the paraffin ap-

paratus of match machines. In the present instance there are four of these paraffin-supply reservoirs, but, of course, their number may be increased or decreased as occasion may require.

5 Bolted or otherwise secured upon each of the upper edges of the side walls of the tank C is a channeled or trough-like structure D, comprising a bottom 1, sides 2 and ends 3, such structure extending throughout the 10 length of the tank, or nearly so. Along the inner side walls of the respective structures are parallel rails 4 which constitute a continuation of the trackway α for the chain after it leaves the impregnating tank. 15 These rails are preferably secured to the structure by through bolts 5 disposed transversely of the structure, which latter is provided at intervals between its walls with distance pieces 6 through which the bolts 20 extend. The bolt holes 7 in the structure are elongated vertically in order to permit limited adjustment of the rails in respect to the level of the paraffin. The rails decline gradually from the front to the rear of 25 the tank C and are then curved upwardly to and merged with a horizontal continuation α^2 of the trackway for the chain, whereby the said chain, with its load of impregnated 30 splints, is gradually lowered as it passes into and through the tank, so as correspondingly to depress the splints into the liquid, and then, the chain is quickly raised to lift the splints from the liquid as 35 they emerge from the rearward end of the tank. As the wet splints pass into the molten paraffin a violent boiling ensues, and the solvent is thus driven from the splints in the form of steam or vapor.

40 In order to maintain the level of the paraffin the upper edges of the side walls of the tank, adjacent the respective reservoirs, are recessed as at 8, to provide overflow openings at the proper level from the 45 tank to the reservoirs; and in order to preclude the passage of air through the overflow openings curtains, as 9, are arranged in front of the respective openings and extended down into the paraffin contents of the 50 adjacent reservoirs, thus forming a paraffin seal. Each of these curtains preferably comprises a piece of sheet-metal having its ends and upper edge bent or flanged and disposed against the inner wall of the reservoir 55 to provide therefrom a vertical duct or passage for the overflowing liquid of the tank. The upper flanged portion of the curtain extends above the reservoir and is conveniently secured to the proximate side of 60 the channeled structure, as by the screws 10.

Upon the sides of the respective channeled structures, throughout their entire length, is supported a hollow or chambered hood E, the interior of which communicates with 65 and forms, in effect, a continuation of the

channels of the structures. This hood is provided with a central uprising neck-portion 11 with which its interior communicates, and this neck-portion opens into an air-trunk 12 leading to a fan or other appropriate air-exhausting medium. The hood is preferably constructed of two longitudinal body sections 13 having semi-circular neck portions formed with flat abutting walls 14 which are bolted together. The central partition thus provided in the neck of the hood divides the air-exhaust and insures a more uniform distribution thereof in the two longitudinal chambers of the hood. The inner side walls of the channel structures are provided at intervals throughout their length, adjacent the inclined trackway, with apertures 15 through which the steam or vapor, as rapidly as it is generated below the carrier chain, is drawn into the hood, and thence discharged through the air-trunk 12 to a point remote from the machine. In the form illustrated these apertures are of gradually decreasing width in order that the plane of their upper edges shall be below the inclined carrier during 90 its travel above the paraffin tank C. (See Fig. 1).

Preferably a portion of the air for removing the steam or vapor is furnished under pressure immediately below the path of the carrier chain and above the paraffin level. To this end a pipe 16 is arranged medially of and below the carrier chain and is connected at one end with a supply pipe 17 through which the air is forced. The pipe 16 is provided on each side thereof, at or near its top portion, with apertures 18 through which the air is discharged adjacent the under side of the chain and toward the lateral channel structures of the hood. The compressed air is thus delivered at a point where it has the greatest effect to prevent condensation of the steam or vapor on the chain plates, which air, together with the vapor associated therewith, is exhausted through the hood and discharge trunk. It is to be noted that the medial longitudinal portion of the carrier chain is imperforate, and thus free from splints, and hence the subjacent air pipe 16 does not obstruct the course of the depending splints on the chain during their passage through the paraffin bath.

While I have herein shown and described my invention as applied to a vessel in which molten paraffin is employed as the evaporating medium, it is to be understood that any other suitable substance for that purpose may be employed. It is also to be understood that where the solution in the impregnating tank is very hot, say 250° Fahr., more or less, my invention may be applied to that tank in order that the steam and vapor evolved from the contained solution

shall be efficiently removed to avoid condensation on the superposed plates of the carrier chain.

I claim—

5. 1. The combination of a vessel for a vaporizing substance, means for supporting and guiding a splint carrier above the said vessel, whereby the splints on the carrier are progressively treated with the contents of
10 the vessel, and means for exhausting steam or vapor from the space between the carrier and said vessel.

2. The combination with a carrier chain for match splints, and means for supplying an impregnating solution to the depending splints during their travel, of a vessel for molten paraffin through which progress the impregnated splints, and means for removing steam or vapor from the space below
20 the carrier chain while the splints are passing through the paraffin.

3. The combination of a vessel, a laterally arranged channel member thereon communicating with the space above the vessel, means
25 for supporting and guiding a splint carrier through said space, and vapor-exhaust means leading from the interior of said member to a point of discharge.

4. The combination of a vessel, channel members on the respective sides thereof communicating with the space above the vessel, means for supporting and guiding a splint carrier through said space, and vapor-exhaust means leading from the interiors of
35 the respective members to a point of discharge.

5. The combination of a vessel, channel members on the respective sides thereof communicating with the space above the vessel, means for supporting and guiding a splint carrier through said space, a cham-

bered hood communicating with the interiors of the respective members and bridging the path of the carrier, and an air trunk leading from said hood to a point of discharge. 45

6. The combination of a vessel, channel members on the respective sides thereof communicating with the space above the vessel, means for supporting and guiding a splint carrier through said space, vapor-exhaust means leading from the interiors of the respective members to a point of discharge, and an air supply pipe extending longitudinally of said space beneath the carrier and provided with lateral air vents adjacent the carrier. 50 55

7. The combination of a vessel, channel members on the respective sides thereof communicating with the space above the vessel, rails on the inner walls of said members 60 adapted to support and guide a splint carrier within and longitudinally of said space, and vapor-exhaust means leading from the interior of said member to a point of discharge. 65

8. The combination with a vessel and a reservoir laterally thereof, said vessel having an overflow opening leading to the reservoir, of a laterally-arranged channel member on the vessel, a shield extending from the overflow opening down into the reservoir, and vapor-exhaust means leading from the interior of said channel member to a point of discharge. 70

Signed at Barberton, in the county of 75
Summit, and State of Ohio, this 24th day
of April A. D. 1912.

FREDERICK VAN DYKE CRUSER.
